United States Patent Office.

FRANKLIN FIELD, OF TROY, NEW YORK.

Design No. 3,559, dated June 29, 1869.

DESIGN FOR A PAPER COLLAR.

The Schedule referred to in these Letters Patent and making part of the same.

To all whom it may concern:

Be it known that I, FRANKLIN FIELD, of the city of Troy, county of Rensselaer, and State of New York, have invented or produced a new and original Design for Ornamenting the Fronts of Paper Collars; and I do hereby declare that the following is a full, clear, and exact description of the said design, reference being had to the accompanying drawing, with the letters of reference marked thereon, which drawing represents a paper collar with my design stamped or embossed upon the front thereof.

This design is applied to the vertical or nearly vertical edges of a "turn-down" or Byron collar, A.

It consists of a narrow, flat raised surface, *b* *c* *b*, stamped or embossed upon the ends of the turned-down portion of a collar, in the form of a triangle, the base of which is the edge *b* *b* of the collar, and the apex of which is at C.

Along this raised surface, and on the inside of the triangle, is a row of indentations, in imitation of stitching, as shown in the drawing.

The effect is to make the article appear as though the corners of the turned-down portion were folded back upon the outside of the same.

What I claim as my invention or production, and desire to secure by Letters Patent, is—

The design for the fronts of paper collars, substantially as hereinbefore shown and described.

In witness whereof, I have hereunto set my hand, this 20th day of May, 1869.

F. FIELD.
